[57] CLAIM

The ornamental design for a child's house slipper, as shown and described.

DESCRIPTION

FIG. 1 is a right side elevational view of a child's house slipper showing my new design;

FIG. 2 is a left side elevational view thereof;

FIG. 3 is a bottom plan view thereof, the broken line
indicating visible stitching therein;

FIG. 4 is a top plan view thereof;

FIG. 5 is a rear elevational view thereof, the broken lines indicating visible stitching therein; and,

FIG. 6 is a front elevational view thereof.

FIG. 1

FIG. 3
